(57) **CLAIM**

The ornamental design for a upright power terminal, as shown and described.

DESCRIPTION

FIG. 1 is a perspective view of a upright power terminal with a first component and a second component, and shows relative positions of the first component and the second component;

FIG. 2 is a front, top, and right side perspective view of the first component showing my new design;

FIG. 3 is a front plane view thereof;

FIG. 4 is a back plane view thereof;

FIG. 5 is a left side view thereof;

FIG. 6 is a right side view thereof;

FIG. 7 is a top plan view thereof, and

FIG. 8 is a bottom plan view thereof;

FIG. 9 is a front, top, and right side perspective view of the second component showing my new design;

FIG. 10 is a front plane view thereof;

FIG. 11 is a back plane view thereof;

(Continued)

FIG. 12 is a left side view thereof;
FIG. 13 is a right side view thereof;
FIG. 14 is a top plan view thereof; and,
FIG. 15 is a bottom plan view thereof.
